UNITED STATES PATENT OFFICE.

EDWARD NELSON, OF EVERETT, AND GEORGE F. HIGGINS, OF MELROSE, MASSACHUSETTS; SAID NELSON ASSIGNOR TO SAID HIGGINS.

COIN-CONTROLLED LOCK.

Application filed January 5, 1921, Serial No. 435,140. Renewed September 30, 1927.

The present invention relates to check or coin controlled locks and more particularly to coin controlled locks of the type that are adapted for use on the doors of cabinets.

- 5 The object of the present invention is to provide a novel and improved coin controlled lock which is simple and durable in construction, and certain and reliable in operation.
- 10 The several features of the present invention will be clearly understood from the following description and accompanying drawings, in which:

Figure 1 is a front elevation of a door and a door frame with a coin controlled lock applied thereto embodying the features of the invention in their preferred form, with the parts of the lock shown in locked position; and Fig. 2 is a similar view but with the parts of the lock shown in a position which they assume following the insertion of a coin; Fig. 3 is a view similar to Fig. 1 with a portion of the front wall of the door broken away; Fig. 4 is a view similar to Fig. 3 but with the parts of the lock shown in full lines in the same position as shown in Fig. 2 and by dotted lines in unlocked position; and Fig. 5 is a horizontal sectional view taken on the line 5—5 of Fig. 1.

30 The present embodiment of the invention is illustrated in the drawings as applied to a door 2 which is hinged at 4 on a frame 6. The door is provided with front and rear walls 8 and 10, respectively, which are constructed and arranged to provide a space between them, in which are mounted the operating parts of the illustrated lock. These parts comprise a pair of locking bolts 12 which are arranged adjacent opposite longitudinal edges of a horizontal plunger 14 and are slideable into and out of engagement with locking slots 15 in the door frame. The bolts and plunger are made of sheet metal and are located in the same vertical plane.

45 When the bolts are in locked position as shown in Figs. 1 and 3, they are securely held from longitudinal movement by stop shoulders 16 formed thereon that are arranged at opposite sides of stop pins 18 secured to the front and rear walls of the door.

50 The forward portion of the inner edges of

the bolts engage bars 20 secured to the front or rear wall of the door, and the ends of inwardly extending arms 22 formed on the rear portion of the bolts engage the opposite 55 longitudinal edges of the coin actuating plunger 14, the bolts being held in engagement with the bars 20 and the plunger 14 by means of leaf springs 24 having one end engaging the outer longitudinal edges of the 60 bolts and their other end secured to a wall of the door.

The plunger 14 is guided at its forward end by a pair of bars 26 secured to the front or rear wall of the door and spaced to engage the longitudinal edges of the plunger, and the rear end of the plunger is guided by a knob 28 secured thereto which extends through an elongated slot 30 in the forward wall of the door. The forward wall of the 70 door is provided with a circular aperture 32 to permit the insertion of a coin between the guide bars 26 and adjacent the forward end of the plunger 14 which is shaped to fit the edge of the coin.

75 When no coin is inserted in the device and the bolts are locked, the forward movement of the plunger 14 is limited by engagement with the inner longitudinal edges of stop arms 36 projecting inwardly from the forward portions of the bolts, so that the locked condition of the bolts will not be thereby affected. To unlock the bolts, the operator inserts a coin in the aperture 32 and then by means of the knob 28 moves the plunger 14 forwardly to the limit of its movement, and during this movement of the plunger the edge of the coin engages inclined surfaces 38 formed on the ends of the stop arms 36 which swings the forward ends of the 80 arms outwardly to permit the coin and the plunger 14 to pass between the stop arms. This forward movement of the plunger 14 past the stop arms 36 is limited by the engagement of the knob 28 with the forward 85 end wall of the slot 30. When the plunger has thus reached the limit of its forward movement, transverse slots 40 formed on its longitudinal edges are positioned to register with the ends of the arms 22, whereupon 90 the arms 22 are caused to engage the slots 40 by the action of the springs 24, the rear ends

of the locking bolts 12 being thereby carried downwardly to the position shown in full lines in Fig. 4 to position the forward locking shoulders 16 so that the stop pins 18 are 5 out of the path of said shoulders. The bolts 12 being thus connected with the plunger 14, the operator moves the plunger rearwardly carrying the bolts therewith out of engagement with the door frame, the shoulders 16 10 passing by the stop pins 18. This movement of the bolts and plunger is limited by the engagement of shoulders 42 formed on the outer longitudinal edges of the bolts with the stop pins 18, as shown by dotted lines in 15 Fig. 4.

To re-lock the device, the operator, after the door is closed, returns the plunger and bolts to their advanced position, as shown in full lines in Fig. 4, the forward ends of 20 the bolts being thereby positioned in the locking slots 15 in the door frame, and the space between each pair of stop shoulders 16 being positioned in alignment with the stop pins 18. The operator then swings 25 the rear ends of the bolts outwardly to disengage the arms 22 from the slots 40 which permits the plunger to be moved rearwardly to carry the slots 40 out of register with the arms 22, so that upon releasing the rear 30 ends of the bolts, the bolts will be locked in position. To thus swing the rear ends of the bolts outwardly, the rear ends of the bolts are provided with apertures 44 into which suitable tools may be inserted for this 35 purpose, the forward wall of the casing being provided with slots 46 to permit the insertion of the tools in the apertures.

It will be noted that the parts of the preferred construction of the lock above described are arranged symmetrically at opposite sides of the coin actuating plunger so that, by inverting the door to which a lock is applied, the door may be hinged to swing either to the right or left. It will, therefore, 40 be apparent that the illustrated lock is particularly adapted to be used on cabinets in which two series of doors are arranged at opposite sides of a single coin chute leading to a coin receptacle near the bottom of the 45 cabinet, one series of doors being hinged to swing to the right and the other to the left. The construction of the lock as above described enables the doors of both series to be of the same construction.

It will also be noted that in the lock 50 above described, the locking bolts engage the door frame close to and at opposite sides of the path of the coin and thus hold this portion of the door rigidly in position 55 and prevent it from being sprung away from the frame to allow the coin to be removed before passing through the coin chute.

While it is preferred to employ the specific construction and arrangement of parts

illustrated and described, it is to be understood that this construction and arrangement is not essential except so far as specified in the claims, and may be changed or modified without departing from the broader features of the invention. 70

The nature and scope of the present invention having been indicated and a device embodying the several features of the invention in their preferred form having been 75 specifically described,

What is claimed is:

1. A coin controlled lock having, in combination, a bolt movable into and out of locking position, and means for locking the 80 bolt in locking position and for releasing and withdrawing the bolt from locking position, comprising a coin actuating plunger, a stop for limiting the movement of the plunger in one direction when the bolt is 85 locked, and means cooperating with a coin during a movement of the plunger in said direction for rendering the stop ineffective and for releasing the bolt, and cooperating members on the bolt and plunger constructed and arranged to operatively engage when the bolt is released to effect the withdrawal of the bolt from locking position during the movement of the plunger in the opposite direction. 90

2. A coin controlled lock having, in combination, a bolt movable into and out of locking position, and means for locking the bolt in locking position and for releasing and withdrawing the bolt comprising a coin 100 actuating plunger, and means cooperating with a coin during the movement of the plunger in one direction for releasing the bolt, and cooperating members on the bolt and plunger constructed and arranged to operatively engage when the bolt is released to effect the withdrawal of the bolt during the movement of the plunger in the opposite direction. 105

3. A coin controlled lock having, in combination, a bolt, movable into and out of locking position, means for locking the bolt in locking position and for releasing and withdrawing the bolt comprising a coin actuating plunger, and means cooperating 110 with a coin during the movement of the plunger in one direction for releasing the bolt, and connections between the bolt and plunger for effecting the withdrawal of the bolt during the movement of the plunger in 115 the opposite direction when the bolt is released. 120

4. A coin controlled lock having, in combination, a bolt having an inclined surface thereon movable into and out of locking position, and means constructed and arranged for locking the bolt in locking position and for releasing the bolt to enable it to be withdrawn from locking position comprising a plunger movable in one direction to bring a 130

coin into engagement with said inclined surface to release the bolt.

5. A coin controlled lock having, in combination, a bolt movable into and out of locking position, and means for locking the bolt in locking position and for releasing and withdrawing the bolt comprising a coin actuating plunger, and means comprising a member carried by the bolt adapted to be engaged by a coin during a movement of the plunger in one direction to cooperate with the coin to release the bolt, and connections between the bolt and plunger for withdrawing the bolt during the movement of the plunger in the opposite direction.

6. A coin controlled lock having, in combination, a pair of bolts movable into and out of locking position, and means for locking the bolts in locking position and for releasing the bolts to enable them to be withdrawn from locking position, comprising a coin actuating plunger, and means cooperating with a coin during the movement of the plunger in one direction for releasing the bolts to enable them to be withdrawn.

7. A coin controlled lock having, in combination, a pair of bolts movable into and out of locking position, means for locking the bolts in locking position and for releasing 20 and withdrawing the bolts from locking position comprising a coin actuating plunger, means cooperating with a coin during the movement of the plunger in one direction for releasing the bolts, and connections between the bolts and plunger for withdrawing the bolts upon movement of the plunger in the opposite direction.

8. A coin controlled lock having, in combination, a pair of bolts movable into and out of locking position, and means for locking the bolts in locking position and for releasing and withdrawing the bolts comprising a coin actuating plunger interposed between the bolts, means cooperating with a coin upon movement of the plunger in one direction for releasing the bolts, and cooperating members on the bolts and plunger for withdrawing the bolts upon movement of the plunger in the opposite direction.

50 9. A coin controlled lock having, in combination, a bolt movable into and out of locking position, means for locking the bolt in locking position and for releasing and withdrawing the bolt comprising a coin actuating plunger, cooperating members on the bolt and plunger arranged to engage when the plunger is moved in one direction to a definite position to retract the bolt upon movement of the plunger in the opposite direction, and a stop for preventing movement of the plunger to said position adapted to be rendered ineffective by engagement with a coin during movement of the plunger in the direction toward said position.

65 10. A coin controlled lock having, in com-

bination, a bolt movable into and out of locking position, means comprising a bolt stop and a coin actuating plunger for locking the bolt in locking position said plunger being constructed and arranged to release the bolt from the stop when the plunger is moved in one direction to a definite position, and a stop for preventing movement of the plunger to said position adapted to be rendered ineffective by the engagement of a coin therewith during movement of the plunger in said direction.

11. A coin controlled lock having, in combination, a bolt movable into and out of locking position, a fixed stop and a cooperating stop shoulder on the bolt for locking the bolt in locking position, a coin actuating plunger provided with a slot, an arm on the bolt in sliding engagement with the plunger adapted to enter said slot to release the stop shoulder from the fixed stop, when the plunger is moved in one direction to a definite position, a plunger stop for limiting the movement of the plunger in said direction to prevent the plunger from being moved to said definite position adapted to be released to permit the plunger to be moved to said definite position by engagement with a coin during the movement of the plunger in said direction.

12. A coin controlled lock having, in combination, a locking bolt, a coin actuating plunger, and means controlled by a coin when actuated by the plunger in one direction for connecting the plunger and locking bolt to allow the locking bolt to be withdrawn by a movement of the plunger in the opposite direction.

13. A coin controlled lock having, in combination, a locking bolt, a coin actuating plunger, means to connect the locking bolt and plunger when the plunger reaches a certain position, and a stop to prevent movement of the plunger to such position operable by a coin actuated by the plunger to allow the plunger to move to such position.

14. A coin controlled lock having, in combination, a coin actuating plunger, a locking bolt having a stop projection extending into the path of the plunger and a withdrawing projection bearing against a side of the plunger, the stop projection being arranged to be moved by a coin actuated by the plunger and to be held out of stopping position by the plunger, and the withdrawing projection being arranged to engage a slot in the plunger and to be held in said slot by the engagement of the stopping projection with the plunger.

15. A door provided with a lock comprising a pair of coin controlled locking bolts, and a coin actuating plunger interposed between the bolts, the parts of the lock at opposite sides of the plunger being arranged symmetrically to permit the door to be

hinged to swing either to the right or left about a vertical axis by inverting the door.

16. A device of the class described having, in combination, a door, a door frame 5 on which the door is hinged, and a coin controlled lock for locking the door to the door frame comprising a coin actuating plunger

and a pair of locking bolts for engaging the door frame close to and at opposite sides of the path of a coin actuated by the 10 plunger.
